UNITED STATES PATENT OFFICE.

WILLIAM COTTRELL, OF LOS ANGELES, CALIFORNIA.

CONCENTRATOR.

1,332,863.

Specification of Letters Patent.

Patented Mar. 2, 1920.

Application filed May 18, 1918. Serial No. 235,310.

To all whom it may concern:

Be it known that I, WILLIAM COTTRELL, a citizen of the United States, residing at Los Angeles, in the county of Los Angeles and 5 State of California, have invented new and useful Improvements in Concentrators, of which the following is a specification.

This invention relates to a concentrator having a table with riffles thereon, and in 10 which either air or water may be used as the concentrating agent.

The ultimate object of this invention is to provide a concentrator having a high capacity, a high extraction, which is simple 15 and requires little attention to its operation.

Specific objects of this invention are first, to provide a concentrator of the class described in which the concentrating fluid agent continuously maintains the committed 20 ore carrying stuff in such state of separation and suspension that the ore may sink to the bottom, and the gangue or tailings rise to the top of the riffles; second, to provide a table of such character that the ore travels substantially parallel with the riffles, while the tailings have a movement 25 transverse to the riffles; third, to provide crowders in the riffles to assist in moving the tailings transverse to the riffles so as to increase the capacity of the machine; and 30 fourth, to provide means to carry away the dust which is created by dry separation.

I accomplish these objects by means of the embodiments of my invention illustrated 35 in the accompanying drawings, in which:

Figure 1 is a side view in elevation of a concentrator arranged to use air as the concentrating agent. Fig. 2 is a vertical section as seen on the line 2—2 of Fig. 1. Fig. 40 2^a is a plan view of the hopper as seen looking in the direction of the arrows 2^a in Fig. 2. Fig. 3 is an end elevation of the tail end of the table. Fig. 4 is a fragmentary plan view of the tail end of the table. Fig. 4^a is 45 a section as seen on the line 4^a—4^a of Fig. 4. Fig. 5 is a diagrammatic plan view of the table. Fig. 6 is an enlarged vertical section through the riffles on the table as seen on the line 6—6 of Fig. 5. Fig. 7 is an enlarged 50 fragmentary plan view of a crouder in position between two riffles. Fig. 8 is a fragmentary plan view of another type of crouder disposed in a riffle.

Referring particularly to Fig. 1, A indi-

cates the foundation frame, which supports 55 the table B. A dust separator is indicated by C. Communicating with the dust separator is a blower D, which discharges into the air chest of the table.

The table is supported upon the foundation frame by means of leaf springs 9, 10 and 11 and is transversely inclined. This construction permits movement of the table transverse to the springs. Secured to the foundation frame is a standard 12 having 60 a block 13 mounted upon its top beneath the table. Mounted upon one end of the block is a buffer cushion 14 disposed to engage a cross piece 15, which is secured to the under side of the table. Fixed to the underside of 65 the table is a bracket 16, through which passes a rod 17. The rod is slidably mounted in standard 12, and mounted thereon between its head and the standard is a compression spring 18. The head may be adjusted to vary the spring tension, and the buffer and cross piece serve to jolt the table. 70

The table comprises a casing 19 having a hinged door 20 disposed above a launder 21. A riffle board 22 divides the casing into 80 two compartments, the lower one forming an air chest, and the upper one a dust chamber.

Communicating with the dust chamber at the upper side thereof is a hopper 23, through which material is delivered to the 85 riffle board. A gate 24 controls the feed of material onto the table.

Referring particularly to Figs. 5 to 8 inclusive, 25 indicates riffles which extend longitudinally of the riffle board from the head end H to the tail end T. These riffles are parallel, and due to the shape of the board increase in length from the upper side to the lower side. The inclined side of the riffle board is closed by a board 26 so that material which reaches the end of the upper riffles will have to travel transversely toward the tail end thereof. It will be noted that the riffles extend the full length of the board. 90

The riffle board is preferably formed of sheet metal corrugated to form channels angular in cross section. Distributed along one side of each of the channels are small perforations 27. Upon the opposite side of each of the channels are small perforations 28. In the channels are crowders 29 which are preferably formed of sheet metal and are 95 100 105

tetrahedrons or double wedges. It will be noted that one exposed face of each of the crowders inclines upwardly and rearwardly, while the other exposed face inclines upwardly and forwardly. It is preferable that the top edge of the crowder be spaced a short distance below the tops of the riffles. The crowders are distributed over the board so that there are several in each riffle channel.

10 The riffles communicate at the tail end with a common inlet to spouts 30. There are three spouts shown herein having the common inlet separated by gates 31. The gates are fixed to shafts 32, which extend 15 through the casing and are bent upwardly to form arms by which they may be turned. The shafts 32 are of spring metal and the ends thereof engage with a ratchet 33 so that they may be locked in position. A 20 spout 34 is connected to the end of launder 21. The mineral as it leaves the ends of the riffles discharges into the spout inlet and is separated into different classes, although the 25 number of classes may be varied by using more or less spouts. By shifting the gates 31, adjustment may be made so that any one spout will receive ore from a variable number of riffles. The tailings discharge into spout 34.

30 The discharge of the blower D is connected by a pipe 35 to the air chest to which it supplies air under pressure. The air then passes through the perforations 27 and 28 in the riffle board, upwardly inclined currents of air from opposite directions meeting in the spaces between riffles and creating air eddies, which agitate the material and tend to hold it in suspension as well as stirring it up. However, the air currents 40 have no tendency to blow the material off from the table. The pipe 35 is flexible to permit movement of the table with respect to the blower which is fastened to the foundation frame A.

45 Connected to the dust chamber is a flexible pipe 36, which discharges into a dust separator C. The dust separator C is mounted upon standards 37, which are fixed to the foundation frame. The dust separator may 50 be of any well known type, and as it forms no part of the invention will not be described. Leading from the air discharge of the dust separator to the inlet of the blower is a pipe 38. Any dust which is raised on 55 the riffle table will be sucked through the dust separator, and the clean air will pass to the inlet of the blower.

The table B is vibrated by means of an eccentric 39 fixed to a shaft 40, and which 60 may be made adjustable so that the proper overbalance may be obtained. A pulley 41 is fixed to shaft 40 for rotating the eccentric. The pulley 41 is rotated by means of a belt 42 passing over a pulley on the drive 65 shaft 43. The springs 9, 10 and 11 assist

in the movement of the table, the jolting occurring when buffer 14 strikes cross piece 15.

As the table is vibrated, and material fed to the upper side of the hopper the material spreads itself thereover, the heavier particles gravitating to the bottom of the grooves. The lighter material gradually moves over the top of the riffles toward the lower side of the table. Some of the heavy particles finally reach the board 26, where it is prevented from moving further longitudinally, and when the riffles spaces become filled with mineral at those ends, it crowds over and works itself transversely toward the spout at the tail end. The air which enters the 80 riffles stirs up the material, tends to hold it in suspension, but does not blow it off the table.

Due to the fine and closely grouped apertures, a low air pressure and a low air stream 85 velocity may be maintained, thereby producing a maximum and evenly distributed agitation, and the material is not blown off the table. It will also be noted that the apertures are grouped so as to leave an imperforate space near the bottom of the valleys. This space is a dead space in which the values may collect and remain undisturbed by 90 the air. These features of construction all increase the efficiency of separation.

95 The crowders 29 produce the same effect as the board 26 in forcing the tailings transversely, but permit the heavy particles to move over the crowders and continue along the riffles. The board 26 and crowders perform substantially all the work of moving the tailings transversely of the table. With this construction separation takes place all over the table so that there is a high extraction.

100 I have described the operation of the device as a dry concentrator. However, while the table is very effective when so used, it may be used as a wet concentrator. In such case the blower B would be replaced by a 110 pump, and there would be no need of a dust separator. The table may also be used with the crowders and without the water being supplied through the riffle boards, that is, the water may be fed upon the board at the 115 head end.

105 What I claim is:

110 1. A concentrating table having riffles extending longitudinally thereof, means inclining toward the tail end of said table to crowd stuff transversely, apertures in said 115 riffles opening into the spaces therebetween so as to direct fluid upwardly thereinto, said apertures being grouped to end short of the bottom of the spaces between said riffles so 120 as to form a dead space at the bottom.

125 2. A reciprocable concentrating table having riffles extending longitudinally thereof, means inclining toward the tail end of said table to crowd stuff transversely, closely 130

- grouped fine apertures in said riffles opening into the spaces therebetween so as to direct opposing currents of fluid from both sides of said spaces upwardly normal to the direction of motion of said table.
3. A reciprocable concentrating table having riffles extending longitudinally thereof, means inclining toward the tail end of said table to crowd stuff transversely, closely grouped fine apertures in said riffles opening into the spaces therebetween so as to direct opposing currents of fluid from both sides of said spaces upwardly normal to the direction of motion of said table, said apertures being grouped to end short of the bottom of the spaces between said riffles so as to form a dead space.
4. A concentrating table having riffles, crowders in the spaces between said riffles, said crowders having surfaces inclining upwardly toward the tailings end with respect to the surface of the table.
5. A concentrating table having riffles, crowders in the spaces between said riffles, said crowders having surfaces arranged diagonal to said riffles and inclining upwardly toward the tailings end with respect to the surface of the table.
6. A concentrating table having riffles, crowders distributed over the surface of the table in the spaces between said riffles, said crowders being tetrahedrons.
7. A concentrating table having riffles, crowders distributed over the surface of the table in the spaces between said riffles, said crowders having surfaces arranged diagonal to said riffles, apertures in said riffles opening into the spaces therebetween so as to direct fluid thereinto.
- 40 8. A concentrating table having riffles, crowders distributed over the surface of the table in the spaces between said riffles, said crowders having surfaces arranged diagonal to said riffles and inclining upwardly toward the tailings end, apertures in said riffles opening into the spaces therebetween so as to direct fluid thereinto.
9. A concentrating table having riffles, crowders in the spaces between said riffles, said crowders being tetrahedrons, apertures in said riffles opening into the spaces therebetween so as to direct fluid thereinto.
10. A concentrating table having riffles, crowders distributed over the surface of the table in the spaces between said riffles, said crowders having surfaces arranged diagonal to said riffles, apertures in said riffles opening into the spaces therebetween so as to direct opposing currents of fluid.
- 60 11. A concentrating table having undulating hill and valley riffles, crowders in the spaces between said riffles, said crowders having surfaces arranged diagonal to said riffles and inclining upwardly toward the tailings end, apertures in the inclined sides of said riffles opening in the spaces therebetween so as to direct opposing currents of fluid from both sides of said spaces.
12. A concentrating table having riffles, crowders in the spaces between said riffles, said crowders being tetrahedrons, apertures in said riffles opening into the spaces therebetween so as to direct opposing currents of fluid from both sides of said spaces.
13. A concentrating table having riffles extending longitudinally thereof, said table inclined transversely, crowders in the spaces between said riffles, said crowders having surfaces inclining upwardly toward the tailings end with respect to the surface of the table.
14. A concentrating table having riffles extending longitudinally thereof, said table being inclined transversely, crowders in the spaces between said riffles, said crowders having surfaces arranged diagonal to said riffles and inclining upwardly toward the tailings end.
15. A concentrating table having riffles extending longitudinally thereof, said table being inclined transversely, crowders in the spaces between said riffles, said crowders being tetrahedrons.
16. A concentrating table having riffles extending longitudinally thereof, said table being inclined transversely, crowders in the spaces between said riffles, said crowders having surfaces arranged diagonal to said riffles, apertures in said riffles opening into the spaces therebetween so as to direct fluid thereinto.
17. A concentrating table having riffles extending longitudinally thereof, said table being inclined transversely, crowders in the spaces between said riffles, said crowders having surfaces arranged diagonal to said riffles and inclining upwardly toward the tailings end, apertures in said riffles opening into the spaces therebetween so as to direct fluid thereinto.
18. A concentrating table having riffles extending longitudinally thereof, said table being inclined transversely, crowders in the spaces between said riffles, said crowders being tetrahedrons, apertures in said riffles opening into the spaces therebetween so as to direct fluid thereinto.
19. A concentrating table having riffles extending longitudinally thereof, said table being inclined transversely, crowders in the spaces between said riffles, said crowders having surfaces arranged diagonal to said riffles, apertures in said riffles opening into the spaces therebetween so as to direct opposing currents of fluid from both sides of said spaces.
20. A concentrating table having riffles extending longitudinally thereof, said table being inclined transversely, crowders in the spaces between said riffles, said crowders

having surfaces arranged diagonal to said riffles and inclining upwardly toward the tailings end, apertures in said riffles opening into the spaces therebetween so as to 5 direct opposing currents of fluid from both sides of said spaces.

21. A concentrating table having riffles extending longitudinally thereof, said table being inclined transversely, crowders in the

spaces between said riffles, said crowders 10 being tetrahedrons, apertures in said riffles opening into the spaces therebetween so as to direct opposing currents of fluid from both sides of said spaces.

In witness that I claim the foregoing I 15 have hereunto subscribed my name this 10th day of May, 1918.

WILLIAM COTTRELL.
